HYDROMECHANICAL MOTOR

Howard F. MacMillin, Mount Gilead, Ohio, assignor, by mesne assignments, to The Hydraulic Press Corporation, Inc., Wilmington, Del., a corporation of Delaware

Application June 1, 1933, Serial No. 673,872

3 Claims. (Cl. 121—38)

This invention relates to hydro-mechanical motors, and in particular, to devices for guiding and retracting the plungers of such motors.

One object of this invention is to provide a hydro-mechanical motor operable in one direction to advance a platen or ram, and retractable in the opposite direction by mechanism consisting of a tie member urged along guide members by means of the coil springs, or similar yielding means, and including a flexible element passing over pulleys in the tie member.

Another object is to provide a hydro-mechanical motor, as described in the preceding paragraph, wherein the tie member is provided with an aperture through which the motor cylinder loosely passes, thereby enabling the motor cylinder to serve as an additional guide member during the reciprocation of the tie member.

In the drawing:

20 Figure 1 is a side elevation of the hydro-mechanical motor and retraction mechanism of this invention.

Figure 2 is a vertical section along the line 2—2 in Figure 3.

25 Figure 3 is a top plan view of the hydro-mechanical motor shown in Figure 1.

Referring to the drawing in detail, Figures 1, 2 and 3 show the hydro-mechanical motor of this invention as consisting of a housing 30 containing a hollow ram chamber 31, to which access is obtained by way of the cover plate 32. The latter is opened by releasing the latch 33, and swings upward on its hinge 34 (Figure 2). Reciprocably mounted within the ram chamber 31 is a movable ram 35, attached to a piston rod 36 as by the set screw 37 in a hollow socket 38. The piston rod 36 passes through a stuffing box 39, having a packing 40 adapted to prevent the passage of liquid out of the ram chamber 31. Beyond the stuffing box 39 the piston rod 36 passes through a drainage chamber 41 with a drainage conduit 42 leading back to the fluid tank, or other source from which the working fluid is obtained. The piston rod 36 then passes through 45 a bore 43 and enters a cylinder chamber 44, situated in the interior of a hydraulic cylinder 45. The drainage chamber 41 and the conduit 42 are adapted to receive fluid escaping from the cylinder chamber 44 through the bore 43, and to 50 convey it back to the fluid tank.

The piston rod 36 terminates in a piston 46 which is adapted to reciprocate in the cylinder chamber 44. To provide this piston reciprocation, fluid pressure is admitted to the cylinder chamber 44 through the coupling 47 and the

conduit 48. The fluid pressure admitted through the above connections forces the piston 46 downwardly and forwardly, pushing the ram 35 forward along its chamber 31 by means of the piston rod 36 attached thereto. Any fluid escaping by the piston 46, or otherwise entering the left-hand end of the cylinder chamber 44, is returned to the tank through the conduit 49.

The pressure fluid forces the piston 46 solely in a forward direction. To retrieve the piston 10 46 and the ram 35 connected to it by the piston rod 36, retrieving means are arranged as shown in Figures 1, 2 and 3. Secured in the end plate 52 of the ram chamber 31 are a pair of guide rods 53, around each of which a helical 15 compression spring 54 is coiled. Arranged to slide to and fro on the guide rods 53 is a plate 55, through the holes 56 of which the guide rods 53 loosely pass. The sliding plate 55 likewise contains a pair of rectangular slots 57, in which 20 are arranged rotatable pulleys 58, around each of which passes a chain 59. One end of each chain 59 is secured to a hook 60, anchored in the end plate 52 of the ram chamber 31, whereas the opposite end of each chain is secured to 25 the movable ram 35 by another hook 61 anchored therein and passing through an aperture 62 in the end plate 52.

In operation, when the ram 35 is forced forward through the action of the pressure fluid 30 upon the piston 46, it pulls the chains 59 with it, causing the sliding plate 55 to move downward upon the guide rods 53, compressing the helical spring 54. When the fluid pressure is released the energy stored up in the helical 35 springs 54 forces the sliding plate 55 backward, causing the chains 59 to pull the ram 35 back to its starting position. When the piston 46 and the ram 35, connected to it, have been forced downward to their extreme forward position, the 40 piston 46 uncovers the port 63, thereby permitting the pressure fluid to rush outward through the conduit 64 to any other hydraulic apparatus which may be desired under certain circumstances to operate in sequence with the previously described 45 apparatus, and forming no part of the present invention.

It will be understood that I desire to comprehend within my invention such modifications as may be necessary to adapt it to varying conditions and uses.

Having thus fully described my invention, what I claim as new and desire to secure by Letters Patent is:

1. In combination, a frame, a hydraulic cyl-

inder thereon, a plunger therein, a platen on said plunger, guide members arranged on opposite sides of said plunger, a tie member mounted for reciprocation along said guide members and having an aperture substantially surrounding the outer surface of said cylinder in relatively slidable relationship therewith whereby the cylinder is adapted to assist the guide members in retaining the tie member in its proper position and path of motion, a flexible member secured at one end to said platen and passing movably over said tie member to an anchorage at the opposite end of said flexible member, and yielding means arranged to urge said tie member in a direction adapted to oppose the working stroke of said plunger.

2. In combination, a frame, a hydraulic cylinder thereon, a plunger therein, a platen on said plunger, guide members arranged on opposite sides of said plunger, a tie member mounted for reciprocation along said guide members and having an aperture substantially surrounding the outer surface of said cylinder in relatively slid-
able relationship therewith whereby the cylinder is adapted to assist the guide members in retaining the tie member in its proper position and path of motion, a flexible member secured at one end to said platen and passing movably over said

tie member to an anchorage at the opposite end of said flexible member, and yielding means ar-
ranged to urge said tie member in a direction adapted to oppose the working stroke of said plunger, said guide members including a pair of rods arranged substantially parallel with the axis of reciprocation of said plunger whereby to cause the tie member, plunger and guide members to occupy the minimum space.

3. In combination, a frame, a hydraulic cyl-
inder thereon, a plunger therein, a platen on said plunger, guide members arranged on opposite sides of said plunger, a tie member mounted for reciprocation along said guide members and having an aperture substantially surrounding the outer surface of said cylinder in relatively slid-
able relationship therewith whereby the cylinder is adapted to assist the guide members in re-
taining the tie member in its proper position and path of motion, a pair of pulleys mounted on said tie member, a pair of flexible members se-
cured to said platen and passing over said pulleys to anchorages at their opposite ends, and yield-
ing means arranged to urge said tie member in a direction adapted to oppose the working stroke of said plunger.

HOWARD F. MACMILLIN.
